UNITED STATES PATENT OFFICE.

LEWIS N. GILMAN, OF ALLERTON, MASSACHUSETTS.

AUXILIARY HEATER.

1,118,196.

Specification of Letters Patent. Patented Nov. 24, 1914.

Application filed March 4, 1912. Serial No. 681,446.

To all whom it may concern:

Be it known that I, LEWIS N. GILMAN, a citizen of the United States, and resident of Allerton, in the county of Plymouth and 5 State of Massachusetts, have invented an Improvement in Auxiliary Heaters, of which the following description, in connection with the accompanying drawings, is a specification, like letters on the drawings 10 representing like parts.

My invention is an auxiliary heater for conserving the heat contained in the smoke-pipe which would otherwise be lost up the chimney, and using said heat for heating 15 the otherwise cold air in a cold-air box or a water coil, and delivering it where desired for house-heating purposes.

In the preferred form of my invention, I provide means for diverting the products 20 of combustion and compelling them and the cold air or water to travel with a retarded movement in a circuitous path in such relation that the heat from said products of combustion is necessarily absorbed or ex- 25 tracted by the cold air or water.

A further object of my invention is to compel all the heat which is transmitted 30 from said diverted products of combustion, to be delivered to the said cold air in the cold-air box or to the water coil, as distinguished from being delivered or radiated 35 into the surrounding room through which the smoke-pipe passes.

Other objects of the invention are to 35 check and steady the draft from a stove or furnace and insure a more even combustion therein, and to provide a smoke-pipe heating device which can be readily attached to any existing pipe and which will be 40 economical to manufacture.

An important feature of my invention is 45 that the cold air flows in actual contact with the direct smoke pipe as well as with the indirect smoke pipe, and therefore is constantly absorbing heat, whether the draft is in one pipe or the other, and it is not necessary to turn the draft into the convolutions of the indirect pipe in order to im- 50 part heat to the cold air.

In the preferred embodiment of my invention herein illustrated, it is to be understood that the water coil, although shown in combination with the air drum and a smoke pipe, may be advantageously 55 utilized without the air drum and in combination alone with a smoke-pipe.

Referring to the drawings, Figure 1 is a view in cross section of the air drum and smoke-pipe; and Fig. 2 is a view partly in cross section of the smoke-pipe, air drum, 60 and a water coil.

A smoke-pipe 1, which is arranged to lead from a stove or furnace upwardly to a chimney, has near its lower end an indirect smoke-pipe 2 opening thereinto as 65 shown at 3, which indirect pipe is arranged in spiral convolutions about the direct pipe 1 and leads back into said pipe at 4 near the chimney. These convolutions are spaced apart and leave a substantial area of the 70 direct pipe exposed, as illustrated in the drawings. Butterfly dampers 5 and 6 of usual type are arranged in the pipes 1 and 2 so that the draft may be diverted from the pipe 1 into the indirect pipe 2. A 75 damper 7 may also be provided in the upper end of the pipe near the chimney. Surrounding the pipes 1 and 2 is a drum 8 having an inlet pipe 9 and a damper 10 arranged therein. The drum 8 is preferably in contact substantially throughout the entire 80 length of the convolutions of the indirect pipe 2, so that air admitted through the inlet 9 will be forced to follow the spiral course of the pipe 2, also flowing around 85 the direct pipe, as will be readily understood on reference to Fig. 1. The upper end of the drum 8 is formed into a heating chamber 11, from which one or more pipes 12 may lead into other rooms or apartments. 90

In order to clean out the indirect smoke-pipe 2, a plurality of openings 13 are arranged, as indicated, normally closed by shutters. It will thus be seen that the smoke, etc., when diverted into the indirect 95 pipe 2, flows through a considerably longer passage than through the pipe 1, and is somewhat retarded thereby and caused to flow evenly and steadily, creating a continuous and uniform draft on the furnace. 100 The cold air coming through the inlet pipe 9 is thus forced into a correspondingly spiral flow and is enabled to absorb practically all the heat which would normally pass through the smoke-pipe up the chimney. But it will be noted that the cold air 105 is actually brought in contact with both the direct and the indirect pipes, and therefore is constantly absorbing heat irrespective of how the draft is turned through said pipes.

Referring to Fig. 2, I have shown a water coil 14 arranged in the smoke-pipe 1 and

also a coil 15 in the indirect pipe 2. A suitable inlet pipe 16 and outlet 17 are arranged at any suitable points throughout the length of the smoke-pipe, these pipes connecting 5 with a radiator or radiators and constituting a part of any well known hot-water heating system. The water in the coil 14 will absorb the heat passing directly through the smoke-pipe 1, and this arrangement may be 10 satisfactory in some instances, but I prefer to use the water coil 15 in the indirect smoke-pipe 2, either with or without the air drum 8.

It will be seen that I have provided a 15 smoke-pipe heating device which is economical to construct, simple to apply to any existing smoke-pipe, efficient in service, and which will absorb and extract practically all of the waste heat normally passing through 20 a smoke-pipe, and prevent the radiation of such heat into the room or apartment through which the pipe passes, and will convey such heat to a different room or apartment. I have found that by means of the in- 25 direct smoke-pipe 2, the draft through a furnace fire is greatly steadied and equalized and the combustion of fuel is rendered uniform, whereas the draft through a direct smoke-pipe is subject to constant variations, 30 such as are caused by varying conditions of wind and weather, and which sometimes re-

suit in an excessive burning up of fuel. However, one of the most important advantages of my invention is that the cold air is constantly being heated by the direct smoke 35 pipe as well as by the indirect smoke pipe when the draft is turned through the latter, and thus even when a fire is being first kindled and started, the cold air will at once begin to absorb heat from the direct smoke 40 pipe before the draft is turned into the indirect pipe.

Having described my invention, what I claim as new and desire to secure by Letters Patent is:

A smoke-pipe heater, comprising an outer drum inclosing a direct pipe, an indirect pipe arranged around said direct pipe in spaced convolutions and in contact with the outer surface of the direct pipe and the inner 51 surface of the drum, forming a helical air passage between said spaced convolutions, and means to turn the draft into either the direct or indirect pipes.

In testimony whereof, I have signed my 5 name to this specification, in the presence of two subscribing witnesses.

LEWIS N. GILMAN.
